UNITED STATES PATENT OFFICE

JOHN S. STOKES, OF HUNTINGDON VALLEY, PENNSYLVANIA, ASSIGNOR TO STOKES AND SMITH COMPANY, OF PHILADELPHIA, PENNSYLVANIA, A CORPORATION OF PENNSYLVANIA

METHOD FOR FORMING BOXES AND THE LIKE

Application filed May 17, 1929. Serial No. 363,828.

My invention relates to the art of forming boxes, particularly wrapped boxes, from a plurality of separate components, sections, or elements of suitable material to form a box, container structure, or equivalent, herein-after generically termed "boxes."

In accordance with my invention, from a strip or roll, preferably disposed adjacent a wrapping station, there is cut a box section or component, which without substantial delay and, as during a wrapping operation, is united with one or more other box-forming components to comprise a box; more specifically, components destined to form end walls of a box are cut from strips or rolls of width corresponding to a dimension of the end walls; preferably the remaining walls, as the bottom and side walls are formed by a single rectangular piece cut from a strip or roll, or removed from a stack of previously cut blanks.

Further in accordance with my invention, the end wall rolls are disposed on opposite sides of the form block structure of a wrapping machine, and the end wall components after severance from their respective rolls are moved toward each other and into engagement with the form block.

My invention resides in the methods of producing a box hereinafter described and claimed and in improvement upon the methods claimed in my co-pending applications Serial Nos. 88,231 and 147,405 filed February 15, 1926 and November 10, 1926, respectively.

For an understanding of my invention, reference is made to the accompanying drawings in which in perspective:

Fig. 1 is a view of a coated tabbed wrapper.

Fig. 2 illustrates a box-forming component.

Fig. 3 is a view of the form block structure of a wrapping machine, and of box-forming components.

Fig. 4 diagrammatically illustrates movement of the box components of Fig. 3.

Fig. 5 is a view of a coated tabbed wrapper

with a box-forming component adhering thereto.

Fig. 6 is a view of a tabbed wrapper in registering relation with a box-forming component, the form block of a wrapping machine being indicated in dotted lines.

Figs. 7 to 11 inclusive, represent, respectively, the successive stages of a box-forming and box-wrapping operation.

Fig. 12 is a view of a continuous strip and a box component cut therefrom.

Figs. 13, 14 and 15 represent the blank of Fig. 12 after or during respectively, scoring, bending and shaping operations.

Fig. 16 depicts the blank of Fig. 12 and the position assumed by parts thereof after the operations of Figs. 12 to 15 inclusive.

Fig. 17 is a view of a coated, tabbed wrapper.

Fig. 18 discloses the blank of Fig. 16 disposed upon the wrapper of Fig. 15.

Figs. 19 to 21 illustrate steps of cutting box components from strips and moving them into registering relation with the other box components.

Fig. 22 is a view of a coated wrapper.

Fig. 23 illustrates a box-forming component having tabs applied thereto.

Fig. 24 is a view of rolls from which box components are cut, and of box component 75 A superimposed upon wrapper W.

Fig. 25 is a view of the box components in box simulating position.

Figs. 26 to 30 inclusive, represent the successive stages of a box-forming and wrapping operation.

Referring to Fig. 1, I have illustrated an individual corner-cut wrapper W, consisting of a single sheet of paper or equivalent material and comprising a bottom section d and front and rear walls e and f. The front wall section e comprises the corner lap sections e1 and e2 while the rear wall section f comprises the corner lap sections f1 and f2. The bottom section d comprises the end wall 90

sections $d1$ and $d2$. Preferably wrapper W is first coated on one face thereof in selected regions or over the entire box engaging area with glue or equivalent adhesive, the application of the adhesive being made while the wrapper is in a stack thereof or, and preferably, after removal from the stack. Thereafter one or more tabs T , of any suitable material, as paper, of any suitable form and size is or are applied to that portion of the coated wrapper destined to come into engagement with the edges, corners or other portions of the box for reinforcing or strengthening the completed box as hereinafter described. Tabs T may be severed as needed from a suitable ribbon or roll, or may be first formed and piled in stacks and withdrawn as and when required as disclosed in my U. S. Patent No. 1,599,500, or preferably 20 may be severed and applied to the wrapper by mechanism disclosed in Rider application Serial No. 294,436, filed April 21, 1928 in which the coating of the wrapper and the application of tabs thereto is effected simultaneously.

The tabbed wrapper with fresh coatings of adhesive on the box-engaging surfaces of the tabs and wrapper is now prepared for application to box-forming components and such application is preferably made promptly, while the coated wrapper W and its coated tabs T are soft and pliable and before the adhesive coatings on the wrapper and tabs have dried, hardened or set.

Referring to Fig. 2, there is illustrated a box-forming component A , section, or element of suitable shape or configuration and of suitable material, as box-board, paper, pasteboard, cardboard or other material, preferably scored or creased as indicated by the two parallel lines a , the scored portions constituting opposite boundaries of a generally rectangular section b forming, upon completion of the box, one face thereof, as the bottom. Lying respectively outwardly of the scored portions of box-forming component A are the substantially duplicate sections c and $c1$ forming, upon completion of the box, opposite faces thereof, as the two sides.

Initially, it is preferable that engagement be effected between box-forming component A and the individual wrapper W in such manner that the section b engage and adhere to bottom section d of the wrapper W . As indicated in Fig. 5, the length of box-forming component A , or the distance along a line a thereof, is such that the component extends from the apexes of the notches on one side of the wrapper to the apexes of the notches on the other side thereof.

A form block or equivalent structure may be so placed as to overlie section b of the component A , the base of the form block corresponding in size with section b , and of a height corresponding generally with the dis-

tance across section c or section $c1$ of box-forming component A , along a line at right angles to the lines a thereof (Fig. 6).

Adjacent the path of movement of the form block and preferably on opposite sides thereof, are disposed the rolls R , $R1$ of suitable box-forming material, such as cardboard, box-board or the like. The width of the roll preferably corresponds to a dimension of a box wall, for example, in Fig. 3, the rolls are equal in width to the shorter dimension of the portion b of box forming component A . From the rolls or strips R , $R1$ are cut the end wall components B , $B1$, whose shorter dimension, for example, corresponds to the height of the finished box, and when the box walls are all of equal height, to the smaller dimension of the front and rear walls c , $c1$. After cutting of the end walls B , $B1$ from their respective rolls, preferably in timed relation to reciprocation of the form block structure F , they are moved toward each other and into engagement with the form block where they may be held by an operator, or retained by suitable mechanism.

Thereafter, the side panels e and f of the wrapper W are moved upwardly, engaging the side sections c , $c1$, of box-forming component A , ultimately assuming a vertical position as shown in Fig. 7, with the inner faces of box sections c , $c1$ engaging the corresponding sides of the form block. Thereafter the now vertical corner lap sections $e1$ and $f1$ of wrapper W are folded inwardly into engagement with box-forming component $B1$ while the corner lap sections $e2$ and $f2$ are likewise folded inwardly into engagement with box-forming component B , Fig. 8.

During this folding operation, the portions of the tabs adhering to the end panels $d1$, $d2$, of the wrapper are pulled out of engagement therewith adjacent the lower corners. Thereafter as the end panels $d1$, $d2$ are folded upwardly into engagement with box-forming components B and $B1$ the portions of the tabs pulled out of engagement with the end panels, and the portions bridging the corner notches, which portions are adjacent and continuing, are folded against the end flaps in the form of small triangles (Fig. 9).

Finally, the portions of the wrapper protruding above the upper edges of the now vertical box-forming walls are folded downwardly and into adhesive engagement with the interior surfaces of said vertical walls to form the completed box illustrated in Fig. 11.

During the wrapping operations, the box-forming components, ends or elements B , $B1$ are firmly and securely bound to the main box-forming component, section or element A , the tabs T reinforcing the union of these elements.

All the foregoing operations may be performed manually. Preferably, however, they will be performed by automatic mechanism.

For example, the individual wrappers W, when in a stack, may be operated upon in an automatic adhesive applying machine, such, for example, as disclosed in Nitsch et al. application Serial No. 69,249 or in the adhesive applying unit G of aforesaid Rider application which simultaneously tabs and cuts individual wrappers. Accordingly individual tabbed wrappers W are fed in succession in proper relation between the form block structure of a wrapping machine as shown by broken lines in Fig. 6. The wrapping machine may be of any suitable character, as for example, of the same general type disclosed in the aforesaid Smith Patents 691,329 and 778,805, or specifically of the type shown in my co-pending application Serial No. 147,405.

In proper timed relation to movement of the form block, the end wall components B and B1 are severed from their respective rolls R, R1 and swung as around the fulcrum m, Fig. 4, to position adjacent the path of movement of the form block or in contact therewith, being retained preferably by clips or the like, or by suction exerted through the form block.

Box-forming components A may be individually fed or transferred in succession between the upper and lower form blocks of the wrapping machine in any suitable manner, preferably, however, in a system such as disclosed in my aforesaid application.

Accordingly, in the wrapping machine, an individual tabbed wrapper W and a box-forming component A come into proper registry with each other in proper relation to the descending form block F to which the box-forming components B and B1 have been secured. In Fig. 6 a stage of the operation is illustrated wherein the upper form-block F has effected engagement of wrapper W and box-forming component A. It will be understood, however, that engagement between the wrapper and box-forming component A may be effected prior to their transportation into the path of movement of the form block. Figs. 7 to 11, inclusive, illustrate the succeeding stages in the box assembly and wrapping operation as effected by the automatic mechanism of the wrapping machine, the wrapper flaps being applied to the box-forming components in suitable sequence and the tabs T being at suitable times applied to and worked around the box corners.

Referring to Fig. 12, the box component A is cut from a roll or strip R3, preferably of width corresponding to the length, or other dimension, of the finished box. Thereafter the component is scored, or creased as at lines a, a, to form the portion b, destined to be the bottom of the box, and the opposite portions c, c1 destined to form the side walls of the box. As above described, the box component A may be individually fed or transferred to a box forming station, as to the form block

structure of a box machine. To facilitate wrapping of the box, and to prevent a bowed appearance of the side walls of the wrapped box, sections c, c1 of component A are folded upwardly, Fig. 14, and inwardly towards each other through a substantial angle and practically flat against the upper surface of the middle portion b. After bending operation, the side walls c, c1 assume the position shown in Fig. 16.

In Fig. 17 there is shown a tabbed wrapper, similar to that of Fig. 1 of this application, and of F 27 of co-pending Rider application Serial No. 294,088, filed July 20, 1928, of which it is characteristic that the tabs T overlie the corner notches of the wrapper.

As has been previously described, the box component A is superimposed upon the wrapper W, by engagement of the form block therewith, during a wrapping operation, or prior to their movement into the path of the form block. The end wall components B, B1 are cut from rolls or strips R, R1 and ultimately assume the position shown in Fig. 21, the components A, B and B1 simulating a box in appearance. Thereafter the wrapping operation is completed, as has been previously described in connection with Figs. 7 to 11.

While all the foregoing operations of Figs. 12 to 21 may be performed manually, preferably they will be performed by automatic mechanism, the cutting of components A from the roll R3, the scoring, bending and transportation thereof successively into the path of the form block of a wrapping machine being in timed relation to the coating and delivery of wrappers W.

The preferred operation is as described, namely, that of utilizing the individual wrapper, and the box, when used, as the sole reinforcing or retaining structure for the box-forming components. It shall be understood, however, that the box-forming components may be first assembled and maintained in box-forming position by suitable structure, as by webs overlying the various corners, and that thereafter the wrapper, or the wrapper and the adhering tabs may be applied in any suitable manner.

Referring to Fig. 22, the wrapper W is plain, that is, not provided with tabs. However, tabs T are applied in suitable position to the box-forming component A.

In this modification of my method, the rolls R, R1 may be on separate and vertical axes, the width of the rolls corresponding to the vertical heights of the end walls. After their severance from the rolls R, R1, the components B, B1 are moved without rotation into engagement with the form block F of a wrapping machine. During the folding of the end flaps e1, and f1 into engagement with the end wall B of the box, the tabs T are simultaneously brought into en-

gagement with the end wall, reinforcing junction therebetween and the side walls c , $c1$. Simultaneously the folding of the wrapper between $d1$ into engagement with end walls or component B1 effects staying or reinforcing of the vertical edges of the box formed by the joinder of side walls c , $c1$ and B1.

The subsequent wrapping operations disclosed in Figs. 27 to 30 inclusive correspond to Figs. 8 to 11 previously described.

Although the foregoing description is limited to the formation of a box from three box-forming components, sections or elements, it shall be understood that my invention comprehends the utilization of greater or smaller number of such components for example, the bottom b may be integral with one only of the side panels, or separate from both, and that my invention comprehends the manipulation and assembly of the desired number of box-forming components in ways specifically different from the corresponding disclosure of this application for example, all of the components may be assembled in box forming relation and thereafter the wrapper applied. Likewise it shall be understood that types of individual wrappers may be utilized differing from the wrapper W herein disclosed, for example wrappers having no corner notching, and that the region or regions where the reinforcing tab or tabs is or are applied may vary as desired to effect proper reinforcing or strengthening in the desired regions of the completed composite box structure, for example, tabs may be applied to overlie the lower, side corners of the box.

Further it will be understood that the sequence of the application of adhesive may vary, for example, the box-forming components may be coated with adhesive, and an uncoated wrapper applied thereto, etc.

It shall also be understood that my invention is not to be restricted to the utilization of a wrapper that is tabbed, strengthened or otherwise reinforced and includes use of a wrapper from which tabbing structure of any kind is omitted. It shall also be understood that although preferably the wrapping operation is completed before hardening of the adhesive coatings on the wrapper or tabs, it comprehends the use of wrappers having secured thereto tabs by adhesive which has hardened or set.

When utilizing a composite wrapper, for example, as illustrated and described in my co-pending application Serial No. 89,127, filed February 18, 1926, it is preferable that the application of the wrapper to the box-forming components be effected prior to material hardening or setting of the adhesive with which the wrapper components are coated, and secured to each other.

The term "scoring" appearing in the ap-

pended claims and applied to an operation performed upon a box component, is used in a generic sense to comprehend "creasing" or equivalent, in which the fibres of the material comprising the component are not cut.

What I claim is:

1. The method of forming a wrapped box from separate box components which comprises cutting box components adapted to form opposite walls of a box from continuous strips and thereafter, without substantial delay, the steps of arranging the separate box components in proper relation, and effecting permanent union of the separate components in box-forming position by a wrapper.

2. The method of forming a wrapped box from separate box components which comprises cutting adjacent a wrapping station, box components forming different walls of the box from continuous strips, and, without substantial delay, thereafter and at the wrapping station arranging the separate box components in proper relation, and effecting permanent union of the separate box components by a wrapper.

3. The continuous method of forming wrapped boxes from separate box components which comprises delivering wrappers in succession to a wrapping station, cutting box components from continuous strips, moving groups of separate components, without substantial delay after said cutting operation, in succession toward the wrapping station, and at the wrapping station effecting in succession permanent union of the components of each group by a wrapper to form a box.

4. The method of forming wrapped boxes from separate box components which comprises moving incomplete groups of box components in succession toward a wrapping station, in timed relation to the arrival of each group at the wrapping station, cutting at least one box component from a continuous strip to complete said group, arranging the separate components of each group in proper relation, and at the wrapping station effecting in succession permanent union of the components of each completed group by a wrapper to form a box.

5. The continuous method of forming wrapped boxes from separate box components which comprises cutting box components in succession from a continuous strip, scoring each of said components in succession to provide sections adapted to form the box bottom and at least one vertical wall, cutting other box components in succession from other continuous strips, arranging the components of a box without substantial delay after they are cut from their respective strips in a box forming group, and in succession effecting permanent union of the separate components of each group in box-forming

position by a wrapper during a wrapping operation.

6. The method of forming wrapped boxes from separate box components which comprises cutting box components in succession from a continuous strip, scoring each of said components in succession to provide sections adapted to form the bottom and opposite walls of a box, arranging in succession each of said components, without substantial delay after said cutting and scoring, with other separate components adapted to form remaining walls of the boxes in proper relation, and in succession effecting permanent union of the separate components of each box by a wrapper during a box-wrapping operation.

7. The method of forming wrapped boxes from separate box components which comprises cutting box components each adapted to form a box bottom and at least one vertical wall in succession from a continuous strip, cutting other box components in succession from other continuous strips, arranging the components without substantial delay after they are cut from their respective strips in successive groups, and in succession effecting permanent union of the separate components of each group in box-forming position by a wrapper during a wrapping operation.

8. The method of forming wrapped boxes from separate box components which comprises cutting box components in succession from a continuous strip, scoring each of said components in succession to provide sections adapted to form the bottom and opposite walls of a box, cutting other box components successively in pairs from continuous strips, arranging the components without substantial delay after they are cut from their respective strips in groups, and in succession effecting permanent union of the separate components of each group in box-forming position by a wrapper during a wrapping operation.

9. The method of forming reinforced wrapped boxes from separate box components which comprises delivering adhesive-coated tabbed wrappers in succession to a wrapping station, cutting at least one box component from a continuous strip, delivering groups of unattached components each group adapted to form a box in succession to the wrapping station, and at the wrapping station, applying the wrappers in succession to groups of components to effect their permanent union in box-forming position with the tabs overlying and strengthening the junction of the separate box components.

10. The continuous method of forming boxes from separate box components which comprises feeding strips of box material from rolls thereof, cutting box components adapted to form opposite box walls from said strips, and without substantial delay after

said cutting, the steps of arranging the components in box-forming position, and uniting them in said position by overlying adhesive-coated sheet material.

11. The continuous method of forming boxes which comprises, cutting at least the box components adapted to form opposite box walls from continuous strips of box material fed from rolls thereof, and without substantial delay after cutting, arranging the unattached components in box-forming position, and uniting them in said position by adhesive-coated sheet material.

12. The continuous method of forming boxes which comprises, feeding a strip of box material from a roll thereof, severing said strip to produce box components each adapted to form the bottom and at least one vertical wall of a box, without substantial delay arranging each component after said cutting with other components in box-forming position, and uniting them by adhesive-coated sheet material.

13. The method of forming boxes which comprises feeding strips of box material from rolls thereof, severing said strips to produce a group of components adapted to form a box, one of said components forming the box bottom and a pair of side walls, arranging each group of components without substantial delay after cutting thereof from said strips in box-forming relation, and uniting the components of each group by adhesive coated sheet material.

14. The method of forming boxes which comprises feeding a strip of box material from a roll thereof, severing said strip to produce main box components each adapted to form a box bottom and a pair of side walls, transporting said components in succession to a box forming station, feeding other strips of box-material from rolls thereof, cutting said strips to form end wall components, transporting pairs of said components in succession to said box forming station, and at said station, in succession uniting said main box components to a pair of end wall components.

15. The method of making boxes which comprises, feeding strips of box material from rolls, severing one of said strips to form box components each adapted to form at least one vertical wall of a box, severing another of said strips to form box components each adapted to form another vertical box wall, arranging a group of components in box-forming position, and applying tab strips to overlie corners of the box formed by said components and permanently to attach said components.

16. The method of making boxes which comprises, feeding strips of box material from rolls, severing one of said strips to form box components each adapted to form the

bottom and at least one vertical box wall, severing other of said strips to form components each adapted to form a vertical box wall, arranging a group of components in box-forming position, and attaching them in said position by tab strips overlying corners of the box formed thereby.

17. The method of making a box which comprises, feeding strips of box material from rolls, severing said strips to form components each adapted to form at least one vertical wall of the box, and without substantial delay arranging the components in box-forming position and attaching them in said position by tab strips overlying corners of the box formed thereby.
